United States Patent Office

Des. 204,471
Patented Apr. 19, 1966

204,471

CULTIVATOR TOOTH

Clifford G. McConnell, North Star Rte.,
Fort Morgan, Colo.

Filed Aug. 6, 1965, Ser. No. 86,475

Term of patent 14 years

(Cl. D39—1)

FIG. 1

FIG. 2

FIG. 3

FIG. 4

FIG. 1 is a side elevational view of a cultivator tooth, showing my new design, the opposite side is similar to the side shown;

FIG. 2 is a top view thereof;

FIG. 3 is a bottom view thereof; and

FIG. 4 is a front elevational view thereof.

I claim:

The ornamental design for a cultivator tooth, as shown and described.
